DRILL COLLAR

Jesse C. Wright, Los Angeles, Calif.; Martha H. Wright, executrix of Jesse C. Wright, deceased

Application August 24, 1936, Serial No. 97,507

23 Claims. (Cl. 255—28)

This invention relates to well drilling equipment and relates more particularly to a drilling stem or drill collar for use in a rotary well drilling string. A general object of this invention is to provide an improved and practical drill collar that materially assists in the rapid drilling of the well and that aids in the drilling of a straight vertical bore.

In the rotary method of well drilling it is the usual practice to interpose a drill collar between the drilling tool and the drilling string. A drill collar consists of one or more cylindrical sections of steel ten feet or more in length and of the same diameter as the drill pipe or slightly larger in diameter than the drill pipe. A drill collar is provided with a fluid conducting bore of less diameter than that of the drill pipe and, therefore, has greater wall thickness than the pipe. Thus a drill collar provides additional weight and rigidity in the drilling assembly immediately above the drilling tool. It has been found necessary to employ drill collars to lend rigidity to the otherwise rather flexible drilling string and to furnish weight to feed or force the drilling tool into the earth formation. When a drill stem is employed it is possible to maintain the drilling string, or a portion of the drilling string in suspension while drilling, utilizing the weight of the drill collar to feed the drilling tool into the earth formation. In the event that hard earth formations are encountered it is necessary to employ a very long drill collar of one hundred feet or more in a length to provide the necessary weight to feed the drilling tool to the formation. If the well bore is crooked or inclined the drill collar has a tendency to fall over against the wall of the bore and further increase the deviation of the drill. This is particularly true where a long drill collar is employed.

Another object of this invention is to provide a drill collar whose weight is concentrated in a minimum vertical zone immediately above the drilling tool to effectively offset the forces tending to cause deviation of the drilling tool from the vertical.

Another object of this invention is to provide a drill collar several times greater in weight than a typical drill collar and that is of minimum length whereby a great weight is concentrated immediately above the drilling tool which weight is imposed on the drilling tool to cause it to drill a vertical bore or to bring it back to a vertical position.

Another object of this invention is to provide a drill collar of sufficient weight that it may con-

stitute the entire drilling load for the drilling tool so that the drilling string need not be employed for drilling pressure and may be maintained under tension or in suspension throughout its entire length.

Another object of this invention is to provide a drill collar of minimum length and of great weight that may fit or operate in the well bore with only slight clearance to act as a stabilizer and a guide bearing and further assist in preventing deviation of the drilling tool from the vertical.

Another object of this invention is to provide a drill collar of minimum length, great weight and maximum diameter that may be readily fished or recovered from the well in the event the drilling string parts above the drill collar. It is customary to employ drill collars of a diameter sufficiently small to allow a wash-over pipe to be run over the drill collar in the event that the drilling string is parted and the drill collar and drilling tool are lost in the well. This requirement has limited the diameter of the typical drill collar and has made it necessary to increase the length of the drill collars when additional weight is required so that drill collars often are one hundred feet or more in length, as described above. The drill collar provided by the present invention may be readily recovered from the well without introducing a wash-over pipe from the surface of the ground and, therefore, the drill collar may be of maximum diameter to operate as a stabilizer or guide and to concentrate its weight immediately above the drilling tool.

Another object of this invention is to provide a drill collar embodying an outer part that constitutes a wash-over pipe for conducting fluid to the bottom portion of the well when it becomes necessary to free the drill collar and the drilling tool from sand or caved in earth formation.

Another object of this invention is to provide a drill collar of the character mentioned in which the inner and outer parts may be rotated relative to one another to assist in freeing the outer part in the event that it becomes sanded in the well bore.

Another object of this invention is to provide a drill collar of the character mentioned in which the outer part may be moved vertically relative to the inner part to free it in the event that it becomes sanded in the well bore.

Another object of this invention is to provide a drill collar of the character mentioned in which the outer part carrying the weight blocks or

weight elements may be disconnected from the inner part and recovered from the well leaving the inner part so that it may be readily engaged and recovered by a suitable fishing tool.

5 A further object of this invention is to provide a drill collar of the character mentioned that may be easily assembled in the drilling string and that embodies parts that may be easily replaced when worn.

10 The various objects and features of my invention will be fully understood from the following detailed description of typical preferred forms and applications of my invention, throughout which description reference is made to the accompanying drawings, in which:

15 Fig. 1 is a view illustrating one form of drill collar of the present invention connecting a typical drilling tool with a drilling string, illustrating the outer part and the weight elements in longitudinal cross section. Fig. 2 is an enlarged longitudinal detailed sectional view of the drill collar illustrated in Fig. 1 showing the inner part and the sub in side elevation. Fig. 3 is a fragmentary longitudinal detailed sectional view of 20 the upper portions of the drill collar with the inner part in elevation, illustrating the fishing or recovering member in connected relation with the outer part. Fig. 4 is an enlarged transverse detailed sectional view taken as indicated by line 25 4—4 on Fig. 1. Fig. 5 is an enlarged transverse detailed sectional view taken as indicated by line 30 5—5 on Fig. 3 and Fig. 6 is a side elevation of another form of drill collar of the present invention illustrating the lower portion of the outer part 35 in longitudinal cross section.

The drill collar of the present invention illustrated in Figs. 1 to 5, inclusive, of the drawings includes, generally, a body 10 to be interposed between the lower end of a drilling string and a 40 drilling tool T, a shell or outer part 11 surrounding the body 10, weight blocks or weight elements 12 carried by the outer part 11 and a member 13 adapted to be run into the well on a fishing string F and connected with the outer part 11 to manipulate or recover the outer part and the weight 45 elements 12.

The body 10 of the improved drill collar is an elongate member for connecting the drilling string S with the drilling tool T. In accordance 50 with the invention the body 10 has considerable strength and rigidity to dependably connect the string S and the tool T and to withstand the various strains to which it may be subjected. The body 10 may be formed of steel and has a 55 substantial wall thickness to have the required strength and rigidity. In practice the body 10 may be in the nature of a typical or common drill collar. In the structure illustrated in the drawings the body 10 is cylindrical and is of uniform 60 external diameter throughout its length. A central longitudinal fluid passage 14 extends through the body 10 from one end to the other to conduct the circulation fluid. Suitable connecting means are provided at the opposite ends of the body 10.

65 A tapered socket 15 may be provided in the upper end of the body 10 to receive a pin part of the drilling string S and a similar threaded socket 16 may be provided in the lower end of the body 10.

The invention provides a sub or connecting 70 member 17 at the lower end of the body 10. The member 17 has a pin 18 screw threaded in the socket 16. The member 17 may be larger in diameter than the body 10 and is provided at its lower end with a socket 19. The socket 19 may 75 receive a threaded pin 20 on the upper end of

the drilling tool T. The drilling tool T is in the nature of a typical fish-tail bit it being understood that the drill collar of the present invention is adapted for use with various types of drilling tools. It is to be noted that the lower end 5 of the body 10 may be closely coupled with the drilling tool T. It is to be understood, however, that a tool joint or the like may be connected between the body 10 and the tool T, if desired. The member 17 is provided with a central longitudinal fluid passage 21 for conducting the circulation fluid downwardly from the passage 14 to the fluid passage of the tool T. The above described body 10 in addition to forming a strong rigid connection between the string S and the tool T provides substantial weight or load for the tool T 10 and operates to carry the various other parts of the drill collar. 15

The shell or outer part 11 of the drill collar is an elongate tubular member surrounding the 20 major portion of the body 10. The outer part 11 performs several functions as will be herein-after described. In the preferred construction the outer part 11 is sufficiently large in internal diameter to surround the body 10 with substantial clearance. This leaves sufficient space within the outer part 11 to contain the weight elements 12 and provide for the circulation of fluid when necessary. The outside diameter of the outer part 11 may be such that the outer part is 30 received in the well bore with only slight clearance so that the outer part may engage the wall of the bore to act as a bearing guide and stabilizer for the tool T. In practice the outer part 11 may comprise a simple length of tubing as 35 illustrated. However, it may comprise several connected lengths of tubing, if desired. The lower end of the outer part 11 is removably supported on the connecting member 17 in a manner to turn with the body 10 and the drilling string 40 S. In the embodiment of the invention being described the sub or member 17 is provided with an upwardly facing external shoulder 22. A clutch ring 23 is secured to the lower end of the outer part 11 and is adapted to seat downwardly 45 on the shoulder 22 to support the outer part. The ring 23 closely surrounds the member 17 to steady and centralize the lower end portion of the outer part 11.

Releasable clutch means normally connects the 50 outer part 11 and the member 17 so that the outer part turns with the body 10. In the simple preferred structure illustrated flat walled notches 24 are provided in the lower end of the ring 23 and correspondingly shaped teeth or lugs 55 25 project upwardly from the shoulder 22 to cooperate with the notches. The notches 24 and the lugs 25 are such that they are properly engaged when the lower end of the ring 23 rests on the shoulder 22 as illustrated in the drawings. It will be apparent that the ring 23 may be released from the shoulder 22 and its clutch lugs 25 by raising the outer part 11 relative to the body 10.

The upper end of the outer part 11 is provided 65 with a head 26. The head 26 may be a tubular or annular member rigidly secured to the upper end of the outer part 11. In the particular case illustrated the head 26 has a downwardly facing shoulder 27 welded to the upper end of 70 the outer part 11. The invention provides spaced longitudinally extending ribs 28 on the interior of the head 26 to cooperate with the exterior of the body 10. The ribs 28 operate to centralize and stabilize the upper portion of the outer 75

part 11. In accordance with the invention a thread 29 is provided on the head 26 to be engaged by a thread on the member 13 as will be subsequently described. In the preferred construction illustrated a tapered pin 30 is provided on the upper end of the head 26 and carries the thread 29. The thread 29 is coarse or heavy and is of a type that may be easily mated with by the thread of the member 13. The ribs 28 cooperating with the body 10 centralize the head 26 relative to the body making the thread 29 readily engaged by the thread of the member 13. Set screws 28^a may be threaded through openings in the head 26 for the same purpose.

15 The weight blocks or weight elements 12 are provided to give the desired weight to the assembly whereby the drill collar is operable to feed or force the drilling tool T into the earth formation during the drilling operation. In the structure illustrated in the drawings the weight elements 12 are within the outer part 11 and are carried or supported by the outer part. It is a feature of the invention that the elements 12 are formed of a material having a high specific 20 gravity. Where I herein employ the term "high specific gravity" I mean a specific gravity greater than the specific gravity of steel of which drill collars have heretofore been constructed. In practice the weight elements 12 may be formed 25 of lead which has a specific gravity much greater than that of steel of which drill collars are usually constructed. Owing to the high specific gravity of the material of which the elements 12 are formed, a relatively small number of elements 30 may be embodied in the drill collar and yet may give the drill collar the desired weight. The invention contemplates the constructing and supporting of the weight elements 12 in various 35 manners. In the particular case illustrated the 40 weight elements 12 are annular or tubular block-like parts supported one upon the other in the annular space occurring between the exterior of the body 10 and the interior of the outer part 11. The tubular elements 12 surround the 45 body 10 and the lowermost element is supported on the upper end of the ring 23. The number of weight elements 12 employed depends upon the drilling conditions it being understood that any desired number of weight elements 12 may 50 be employed. When it is desired to impose a great weight on the drilling tool T a substantial number of blocks or elements 12 may be provided within the outer part 11 in which case the uppermost element 12 may have its upper 55 end adjacent the head 26, as illustrated in the drawings.

In accordance with the invention a fluid passage is provided through the outer part 11 to conduct flushing fluid downwardly to free the outer part in the event that it becomes sanded or muddled in the well. In the construction illustrated in the drawings the blocks or weight elements 12 surround the body 10 with substantial clearance leaving an annular passage P. The upper end of the passage P is in communication with the interior of the tubular head 26. Circumferentially spaced fluid grooves 31 are provided in the exterior of the member 17 and have their upper ends in communication with the lower end of the fluid passage P. The grooves 31 extend downwardly to the shoulder 22 where they communicate with fluid discharge ports 32. The fluid ports 32 extend through the member 17 to its exterior where they discharge the fluid 70 into the well. Fluid discharge ports 32^a may

also be provided in the ring 23 to communicate with the grooves 31. It will be noted that the fluid passed downwardly through the passage P discharges into the well at the lower end of the outer part 11 so that its return upwardly through 5 the well may free the outer part for recovery. The blocks or weight elements 12 preferably fit rather closely within the outer part 11 so that they do not have excessive lateral or horizontal movement.

10 It will be observed that the weight elements at 12 formed of a material having a high specific gravity add materially to the weight of the drill collar so that the drill collar imposes a great weight on the drilling tool T. The elements 12 15 are housed in the outer part 11 so that the weight of the drill collar is concentrated directly above the drilling tool T. The heavy weight elements 12 surround the relatively heavy body 10 and the drill collar is of maximum length. 20 The outer part 11 surrounding and housing the relatively soft weight elements 12 protects the elements against wear and against contact with the wall of the well bore.

25 The member 13 is provided to connect with the outer part 11 of the drill collar to facilitate manipulation of the outer part or recovery of the outer part in the event that it becomes caught in the well or the drilling string S parts above the drill collar. The member 13 is adapted to be 30 run into the well on a recovering string or fishing string F passed downwardly over the drilling string S. In practice the member 13 may be a simple tubular part directly threaded on the lower end of the fishing string F. A socket 33 35 is provided in the lower end of the member 13 to receive the pin 30. A thread 34 is provided on the wall of the socket 33 to mate with the thread 29. The threads 29 and 34 are such that they may be easily made up or threaded together to connect the fishing string F with the outer part 11. When the member 13 is threaded on the pin 30 the fishing string F connected with the outer part 11 through the medium of the member 13 and may conduct flushing fluid to 40 the passage P may also be employed to recover the outer part 11 and the weight elements 12 from the well in the event that the drill collar 45 is lost in the well.

50 In operation the drill collar illustrated in Figs. 1 to 5, inclusive, of the drawings may be connected between the drilling tool T and the drilling string S as illustrated throughout the drawings and run into the well with the tool T in the usual manner. During the drilling operation the weight of the drill collar feeds or forces the drilling tool T downwardly against the earth formation. Owing to the presence of the plurality of weight elements 12 in addition to the relatively heavy body 10, the drill collar is very 55 heavy to urge the drilling tool T downwardly with substantial force. It is important to note that the great weight provided by the drill collar is concentrated immediately above the drilling tool to materially assist in feeding the tool to 60 drill a straight vertical bore. The weight provided by the improved drill collar being concentrated immediately above the drilling tool T offsets or resists the forces which may tend to effect deviation of the drilling tool T from the 65 vertical. The heavy drill collar is rigidly and closely coupled to the tool T and having a center of gravity very close to the tool T urges the tool directly downward even though the earth formation be such that it tends to deviate the tool from 70 75

the vertical. Further, in the event the well bore is crooked or inclined the heavy compact drill collar immediately above the bit and closely coupled thereto feeds the bit directly downwardly to straighten the bore. The drill collar of the present invention embodying the blocks or weight elements 12 may have a weight two or three times greater than a typical drill collar and yet may have a minimum length so that it 10 has little or no tendency to tilt or fall against the wall of the well bore even though the bore be inclined. The outer part 11 of the drill collar may be proportioned to rather closely fit the well bore so that it engages the wall of the bore 15 to act as a guide bearing and to stabilize the bit. This action of the outer part 11 further assists in directing the tool T to drill a straight vertical bore. The outer part 11 of the drill collar may be proportioned as above described 20 without danger of the drill collar becoming immovably caught or sanded in the well. The heavy drill collar absorbs the shocks resulting from the action of the tool T on rough and hard formations.

25 If for any reason the outer part 11 becomes caught or sanded in the well bore the member 13 may be secured to the lower end of a wash-over string F and passed downwardly over the drilling string S to the head 26. Circulation fluid or 30 water may then be pumped downwardly through the string F to flow through the head 26, the passage P, the grooves 31 and the ports 32 and 32^a into the well at the lower end of the outer part 11. After being discharged in the well the 35 fluid passes upwardly around the outer part 11 and may free the outer part so that operations may be resumed. The outer part 11 of the drill collar thus serves as a wash-over pipe always conveniently available at the drill collar. The 40 string F may be rotated to thread the member 13 on the pin 30. The string F may then be raised to disengage the notches 24 from the clutch parts 25 whereupon the string F may be moved vertically, or rotated, or both, to free 45 the outer part 11.

50 In the event that the drilling string S parts or breaks above the drill collar and it becomes necessary to fish or recover the drill collar and the tool T from the well the string F carrying the member 13 is run into the well, the member 13 is engaged over the pin 30 so that the threads 55 29 and 34 engage, and the string F is rotated to thread the member 13 on the pin 30. The string F may then be manipulated and raised in an attempt to withdraw the lost parts from the well. If this attempt fails it may be found necessary to first loosen or free the outer part 11. Circulation fluid or water may be pumped downwardly 60 through the fishing string F to pass through the passage P, the grooves 31 and the ports 32 and 32^a. This fluid under pressure discharged into the well passes upwardly around the outer part 11 and loosens or frees it from the accumulated sand, cuttings, etc. If believed necessary or desirable the string F may be manipulated to move the outer part 11 upwardly whereupon it may be reciprocated or rotated, or both, to free it. When freed the outer part 11 carrying the weight elements 12 may be withdrawn from the 70 well on the string F. The removal of the outer part 11 carrying the weight elements 12 leaves the body 19 exposed for easy engagement by a suitable fishing tool so that the body 19, the tool T and any remaining lower portion of the string S may be readily recovered from the well. The 75

clutch connection between the outer part 11 and the member 17 is sufficiently loose to prevent the transmission of undesirable vibration between the parts and to prevent strains being set up in the connection. The movement between the 5 parts due to the character and looseness of the clutch connection prevents the circulation passage P from becoming sanded up.

Fig. 6 of the drawings illustrates a slightly modified form of construction in which the ring 10 23 of the outer part 11 is threaded to the member 17 on the body 10. The various parts of the drill collar may be constructed and assembled as described above. The notches 24 and the lugs 25 are eliminated, however, and the interior of 15 the ring 23 and the exterior of the member 17 are provided with cooperating threads 40. The threads 40 normally rigidly connect the outer part 11 to the body 10. The threads 40 are preferably left-hand threads so that they may be unthreaded by rotation transmitted through the string F without endangering the threaded joints and connections of the string and without unthreading the threads 29 and 34. It may be preferred to eliminate the fluid grooves 31 and extend the ports 32^a upwardly through the member 17 to have their upper ends in direct communication with the passage P.

20 The operation of the construction illustrated in Fig. 6 of the drawings is substantially the same as the operation of the previously described form of the invention. The threads 40 normally connect the outer part 11 with the body 10 but are such that the outer part 11 may be disconnected from the body 10 for movement relative 25 thereto or for recover from the well. The string F may be connected with the outer part 11 by means of the member 13 as described above and rotated to unthread the threads 40 whereupon the member 11 carrying the weight elements 12 40 may be moved vertically or rotated to free it or may be withdrawn from the well on the string F.

Having described only typical preferred forms and applications of my invention, I do not wish to be limited or restricted to the specific details 45 herein set forth but wish to reserve to myself any variations or modifications that may appear to those skilled in the art or fall within the scope of the following claims.

Having described my invention, I claim: 50

1. A drill collar for use in a rotary drilling string including, a body to be connected in the string and having sufficient strength for the transmission of the forces to which the string is subjected, a tubular part around the body, coupling means on the upper end of the said part 55 for connecting with a washover pipe whereby said part is adapted to operate as a continuation of the wash-over pipe, and means removably connecting the outer part with the body. 60

2. A drill collar for use in a rotary drilling string including, a body to be connected in the string and having sufficient strength for the transmission of the forces to which the string is subjected, an outer part around the body and 65 removably carried by the body to be removable upwardly from the body when the body is connected in the string means on the outer part for coupling with a wash-over pipe, and an element of high specific gravity carried by the outer part. 70

3. A drill collar for use in a rotary well drilling string including, a body, means at the ends of the body for facilitating its connection in the string, an outer part around the body rotatable relative to the body to be freed of material im- 75

- 5 pacted about it, releasable clutch means for holding the outer part against such movement, the outer part being removable upwardly from the body, and coupling means on the outer part for 5 coupling with a wash-over pipe whereby the outer part may be removed from the well by the wash-over pipe.
- 10 4. A drill collar for use in a rotary well drilling string including, a body, means at the ends of the body for facilitating its connection in the string, an outer part around the body, means supporting the outer part on the body, said outer part having a longitudinal fluid passage whereby it may act as a wash-over pipe, and means on 15 said outer part for receiving a fluid conducting string to supply fluid to said passage.
- 15 5. A drill collar for use in a rotary well drilling string including, a body, means at the ends of the body for facilitating its connection in the string, an outer part around the body, a weight element carried by the outer part, means supporting the outer part on the body, said outer part having a longitudinal fluid passage whereby it may act as a wash-over pipe, and means on 20 said outer part for receiving a fluid conducting string to supply fluid to said passage.
- 20 6. A drill collar for use in a rotary well drilling string including, a body, means at the ends of the body for facilitating its connection in the string, an outer part around the body, means supporting the outer part on the body, said outer part having a longitudinal fluid passage whereby it may act as a wash-over pipe, and a member to be run into the well on a flushing string to connect with the outer part whereby the said passage receives fluid from the string.
- 25 7. A drill collar for use in a rotary well drilling string including, a body, means at the ends of the body for facilitating its connection in the string, an outer part, releasable clutch means removably supporting the outer part on the body and connecting the outer part with the body to move therewith, a weight element carried by the outer part, connecting means on the outer part, 30 a member to be run into the well on a fishing string, and connecting means on the member to mate with the first mentioned connecting means whereby the outer part may be recovered from the well.
- 35 45 8. A drill collar for use in a rotary well drilling string including, a body, means at the ends of the body for facilitating its connection in the string, an outer part surrounding the body with clearance and removably carried by the body to be removable upwardly therefrom, coupling means on the outer part for connecting with a pipe passed downwardly over the string, and material of higher specific gravity than the body in the space between the body and outer part.
- 50 55 60 9. A drill collar for use in a rotary well drilling string including, a body, means at the ends of the body for facilitating its connection in the string, an outer part carried by the body and surrounding the body with clearance, and a stack of annular blocks surrounding the body within the outer part.
- 65 70 75 10. A drill collar for use in a rotary well drilling string including, a body, means at the ends of the body for facilitating its connection in the string, an outer part surrounding and removably carried by the body, the outer part having a longitudinal fluid passage extending from its upper portion to its lower portion, and coupling means on the upper portion of the outer part for connecting with a fluid conducting pipe whereby the outer part may act as a wash-over pipe.

5 nected in the drilling string and having a passage for conducting the circulation fluid handled by the drilling string, means for conducting flushing fluid longitudinally of the body to discharge from the lower portion thereof, and connecting means carried by the body for connecting with a wash over pipe to receive fluid therefrom and deliver it to said means.

10 19. A device for use in a rotary drilling string including, a drill collar body to be connected in the string and having sufficient strength for the transmission of the forces to which the string is subjected, a part formed of a material having a higher specific gravity than the body surrounding the body to slide and rotate therewith and removably carried by the body to be removable upwardly from the body when the body is connected in the string, and means connecting the body and said part against relative rotation when in a predetermined relative position.

15 20. A drill collar for use in a rotary well drilling string including, a body, means at the ends of the body for facilitating its connection in the string, a tubular part around the body shiftable relative to the body, there being a longitudinal fluid passage through said part opening into the well whereby the outer part may operate as a wash-over pipe, a weight element formed of a material of higher specific gravity than the body and carried by the said part, and clutch means supporting the outer part on the body whereby the weight of said element is imposed on the string.

25 21. A drill collar for use in a rotary well drilling string including, a body, means at the ends of the body for facilitating its connection in the

string, an outer part fitting the body for rotation relative to the body and for longitudinal movement relative to the body, clutch means removably supporting the outer part on the body, and connecting the outer part with the body to turn therewith when in a predetermined longitudinal position relative thereto, a weight element carried by the outer part, and a member to be run into the well on a fishing string to connect with the outer part to recover the same. 10

22. A drill collar for use in a rotary well drilling string including, a body, means at the ends of the body for facilitating its connection in the string, an outer part carried by the body to be removable upwardly therefrom when the body is connected in the string, the outer part surrounding the body with clearance, a thread on the upper end of the outer part forming coupling means on the outer part for connecting with a pipe passed downwardly over the string, means 15 connecting the body and the outer part releasable by relative rotation between the body and the outer part, and a weight in the outer part.

23. A device for use in a well drilling string carrying a drilling tool including, an inner member connected in the string, a weight rotatable relative to the member and shiftable longitudinally of the member, and parts on the member and weight cooperating when the weight is in a predetermined position longitudinally of the member to detachably couple the weight and the inner member so they rotate together, the weight being removable upwardly from the inner member when the said parts are out of cooperating engagement. 25
